Louis J. Parsons

LOUIS J. PARSONS, OF NEW BEDFORD, MASSACHUSETTS.

Letters Patent No. 83,204, dated October 20, 1868.

IMPROVEMENT IN THILL-GUARDS.

The Schedule referred to in these Letters Patent and making part of the same.

To all whom it may concern:

Be it known that I, LOUIS J. PARSONS, of New Bedford, in the county of Bristol, in the State of Massachusetts, have invented a new and improved "Thill-Guard," in lieu of the safety-strap now used; and I do hereby declare that the following is a full and exact description thereof, reference being had to the accompanying drawings, and to the letters of reference marked thereon.

My invention consists in a metallic guard, firmly secured to the thill, and curved over the axle-tree in such manner that the thill will be held by it in case of the coupling breaking.

The accompanying drawing is a perspective view of a portion of an axle-tree and thill, with my invention applied thereto, in which—

A is a portion of an axle-tree.

B is a portion of a thill.

C is the guard.

Claim.

What I claim as my invention, and desire to secure by Letters Patent, is—

The metallic safety-guard C, for thills of carriages, constructed and operating substantially as and for the purpose set forth and described, and applied in any practical manner.

LOUIS J. PARSONS.
